UNITED STATES PATENT OFFICE.

CHARLES A. DAWES, OF ST. LOUIS, MISSOURI.

COPY-HOLDER.

1,184,327.

Specification of Letters Patent.

Patented May 23, 1916.

Application filed January 29, 1915. Serial No. 5,006.

To all whom it may concern:

Be it known that I, CHARLES A. DAWES, a citizen of the United States, residing in the city of St. Louis, in the State of Missouri, 5 have invented new and useful Improvements in Copy-Holders, of which the following is a complete specification, reference being had to the accompanying drawings.

My invention relates to devices for the 10 more convenient holding of manuscript copy, stenographic notes and note books, or any other matter which it may be desired to transcribe from the original form into finished, complete typewritten or other ex- 15 tended form, upon a typewriting machine, linotype machine, or other apparatus for such purposes commonly used, or for transcribing figures or other matter from the original copy into permanent form in record 20 books, or otherwise, by hand.

The main object of my invention is the 25 production of such copy holder embodying a quick acting, positive and adjustable line indicator, which, by quick and easy manipu- 30 lation of the fingers, may be made to follow the copy downward from line to line as the matter is being copied, and which indicator, upon reaching the bottom of the page, may be instantly returned again to the top, for 35 use upon the succeeding page, by a mere upward movement of the hand.

Another object of my invention is the 40 production of such holder having suitable adjustable and expandible members, whereby copy and manuscript notes, or books or papers of varying thicknesses may be quickly and easily adjusted to the holder, yet permitting said line indicator to lie perfectly flat upon the page, regardless of the thickness 45 of such copy.

Another object is to produce such copy holder having an adjustable frontal bracket, whereby the holder may be more conveniently used with copy or manuscript matter 50 of varying lengths.

A further object is to produce a copy holder of the character described which may be readily folded up into a very compact form and small space for the purpose of 55 packing and shipping in quantities, or for carrying in the hand from place to place.

Still a further object is to produce such holder embodying a simple means for holding pencils, erasers and the like, not in use, 55 through a projecting bottom ledge. And a

still further object is to produce such copy holder adaptable to use in different positions, as for holding in the lap or lying flat on the table for the purpose of taking stenographic notes or other data.

With these and other objects in view, attention is called to the accompanying drawings, to be considered in connection with these specifications, and wherein—

Figure I represents my improved copy 65 holder as same appears in actual use, the line indicator being elevated to the top of the page ready for the operator to touch the sprocket for the purpose of lowering the line indicator upon the page. Fig. II represents the copy holder expanded in full to receive a heavy thickness of manuscript matter, the side bar and paper finger being elevated by pressing together the thumb hooks 70 of the compression spring, and the line indicator being thrown aside to permit of the ready insertion of the copy upon the holder. This manuscript copy being long as well as thick, the adjustable frontal bracket is 75 placed at its lowermost position upon the face of the holder. Fig. III represents the copy holder with the adjustable side bar depressed, and the adjustable frontal bracket raised, thus adapting the holder for the thin and short manuscript shown in this view. 80 The line indicator is shown lying flat across the face of the manuscript. These three views each show also the lower pencil holding ledge with pencils placed thereon. Fig. IV is a perspective side and rear view showing 85 the adjustable side bar and paper finger partly raised by compression of the spring at the back, the line indicator being detached from its socket to show method of mounting 90 same upon its supporting sliding bracket, by means of the connecting U shaped link, and the method of mounting the sliding bracket itself within the longitudinal slot of the adjustable side bar. This drawing also shows 95 the method of forming and mounting the spool and sprocket which controls the line indicator, upon the lower swinging arm, the method of mounting the adjustable side bar upon the upper and lower swinging supports, and the method of connecting the cord 100 controlling the line indicator with the slide- able bracket at the upper end and the spool and sprocket at the lower end, the cord itself running down along the longitudinal slot in the adjustable side bar. Fig. V is a detail 105

110

rear view showing method of forming and assembling the flat compression spring controlling the adjustable side bar with attachments through the connecting arm, and the 5 folding easel which supports the copy holder as a whole. Fig. VI is a detail showing the form of construction of the upper swinging bracket as a whole, made up of its lower supporting member, the depressed 10 lever-like offset, the connecting elbow and the upper paper finger. Fig. VII is a detail drawing showing the method of forming and attaching the adjustable frontal bracket.

Referring now more particularly to the 15 drawings, 1 represents the body of my improved holder, formed preferably in rectangular shape, with downwardly turned side edges 2 and upper edge 3, the lower edge however, being turned forward at an 20 angle to form the pencil holding ledge 4. At suitable points upon the face of the body plate 1 are formed the slots 5 to receive and hold the corresponding studs 6 projecting from the adjustable frontal bracket 7, 25 whereby the latter may be readily adjusted upward or downward upon the face of the holder, as desired, for short or long copy.

The body plate 1 is supported at the back by the easel 8 formed preferably V-shaped 30 from heavy wire, with the diverging prongs 9 extending upwardly, then bent downwardly again to form the elbows 10, and the extremities forming loops 11 around the upper arm 12 of the flat compression spring 35 13, whereby the easel 8 becomes swingingly mounted thereupon so that the prongs 9 may be depressed at will close to the body plate 1, or may be swung outwardly for setting in place for use. When so thrown outwardly, 40 the arms 9 are prevented from too great distension by the elbows 10 coming into contact with the under side of the body plate 1. The flat compression spring 13 is formed preferably from heavy spring wire, with the coil 45 14 to yield additional resiliency, and the two diverging arms 12 and 15, ending in the thumb-hooks 16 after passing through the side edge 2. The said upper arm 12 of the flat compression spring 13 passes through 50 the edge 2 by way of the equi-dimensional hole 17, while for the lower arm 15 the slot 18 is formed through said edge 2, affording to said lower arm 15 and its projecting thumb-hook 16, ample space for upward and 55 downward play therein, while the upper arm 12 is, meanwhile, held immovable. The coil 14 of the flat compression spring 13 is secured firmly at the opposite edge of the body plate 1 upon the lower or under side 60 thereof, by any suitable means, as by the metal strap 19, so that the said flat compression spring 13, being thus firmly secured to the body plate 1, the easel 8, mounted as aforesaid upon the upper arm 12 of the compression spring 13, is thereby afforded

a secure attachment to the body plate 1 for the purpose of supporting the copy holder as a whole.

From a point 20 along the lower arm 15 of the flat compression spring 13, immediately inside the edge 2 of the body plate 1, being looped around said arm at said point, extends upwardly the connecting arm 21, it being in turn, at its said upper end, looped around the U-shaped lever 22 formed as an 75 offset from the lower supporting member 24 of the swinging bracket 23. This upper swinging bracket 23 is eccentrically formed, as shown, consisting of said lower supporting member 24 with its said U-shaped lever 22, the connecting elbow 26 projecting upwardly at an approximate-right angle, and lastly the paper finger 25 returning on a line parallel to the said lower supporting member 24. This lower supporting member 24 is mounted at the back and upper portion of the body plate 1 through the holes 27 formed through the edges 2, and so that the elbow 26 clears the side of the body plate 1 and carries the paper finger 25 to the front of the body plate 1, where it is normally held by the action of the flat compression spring 13, working through its auxiliary elements described, flat up against the face of said body plate 1. At the lower end of the body plate 1, and on the same side thereof from which extend the thumb-hooks 16 and the elbow 26, upon the turned edge 2 is pivoted the lower swinging arm 28, moving up or down on its pivot 29 and carrying midway the rotatable spool 30 bearing its outer, integrally formed sprocket 31, said spool being mounted upon the axle 32 joined rigidly to said arm 28. Between the upper end 33 of said lower swinging arm 28 and the paper finger 25 at a point 34 thereon, is swingingly mounted the adjustable slotted side bar 35, which carries the longitudinal slot 36 along its upper face as mounted, and is of such length as to hold the arm 28 approximately parallel to the elbow 26. Slidably mounted within said slot 36 is the supporting bracket 37, turned with its inwardly flared wings 38 for sufficient frictional hold to the slot 36, and the outwardly looped socket 39, into which is set the pivot prong 40 of the U-shaped connecting link 41, while upon the other prong 42 of said link 41 is swingingly mounted the line indicator 43, in such manner that it may be readily raised and swung aside or back into place at will, it retaining at all times a position approximately at right angles to said adjustable side bar 35. A cord 44 is joined to the spool 30 by one end, the other end being connected to said supporting bracket 37, so that the cord 44 falls inside said longitudinal slot 36 of the side bar 35; and is protected thereby.

In actual use, with the elements of my in-

vention so formed and assembled, it is evident first, that the adjustable frontal bracket 7 may be readily adjusted upon the face of the body plate 1 for long or short manuscript copy, as shown at 45 and 46 respectively; second, that by compressing together the thumb-hooks 16, the leverage action of the flat compression spring 13, the connecting arm 21, the U-shaped lever offset 22 and the connecting elbow 26, will cause the paper finger 25 to swing upward and forward, carrying with it the adjustable side bar 35 and the line-indicator 43, while releasing pressure from said thumb-hooks 16 will, through the normal action of the flat compression spring 13, cause all of said members to relapse and fall flat against the face of the body plate 1, by which arrangement manuscript copy, note books or other matter of varying thicknesses may be readily accommodated, as shown at 45 and 46; third, that owing to the auxiliary effect of the U-shaped connecting link 41, the line indicator 43 will at all times lie snug and flat against the face of the copy 45 and 46; fourth, that a touch of the finger upon the periphery of the sprocket 31 will wind the cord 44 upon the spool 30 drawing after it the line indicator 43, and that said line indicator 43 may be readily returned again to the top of the apparatus by sliding the bracket 37 upward, as desired; fifth, that said line indicator 43 may be quickly swung to or from its place, at will, to facilitate the interchange of copy; sixth, that the ledge 4 affords a convenient means of holding pencils, erasers and the like, not in use; and seventh, that the whole device may be readily folded into neat and compact form, and as quickly unfolded, and set up, as may be desired.

Having thus described my invention, pointing out certain specific forms of construction and methods of assembling the elements thereof, and reserving the right to modify same in minor details so as best to construct my improved copy holder to meet all practical demands, what I claim to be new and patentable is:

1. A copy holder consisting of a body plate, an adjustable, outwardly swinging side bar mounted thereon, a compression spring to control the action of the side bar, a paper finger mounted at the upper end of

the side bar; a line indicator slidably mounted on said side bar; a cord running from the base of the line indicator; a rotatable spool at the base of the body plate.

2. A copy holder consisting of a body plate, an adjustable, outwardly swinging side bar mounted thereon, and a compression spring to control the action of the side bar; a paper finger located at the upper end of the side bar and rigidly connected thereto; an adjustable line indicator swingingly and slidably mounted upon the side bar; a cord running from the base of the line indicator; a rotatable spool located at the base of the body plate and to which the lower end of the cord is attached.

3. A copy holder comprising a body plate, a slotted, adjustable, forwardly swinging side bar; a compression spring to control the action of the side bar; a paper finger rigidly attached at the upper end of the side bar and projected at right angles to the side bar across and parallel to the face of the body plate; a swinging, slidable, adjustable and detachable line indicator mounted on the side bar; a cord running from the base of the line indicator down along the side bar to and around a rotatable spool located at the base of the body plate; a rotatable spool located at the base of the body plate.

4. A copy holder comprising a body plate; a slotted, adjustable and outwardly swinging side bar mounted at one side of the body plate; a compression spring located at the back of the body plate to control the action of said side bar and to hold it normally flat against the body plate; a paper finger mounted at the upper end of the side bar at right angles thereto and parallel to the plane of the body plate; a bracket slidably mounted within the slot of the said side bar and bearing an outwardly extending socket; a line indicator swingingly and detachably mounted in said socket at right angles to said side bar; a cord attached at one end to the sliding bracket, thence passing down along the slot of the side bar and around a rotatable spool; a rotatable spool mounted at the bottom substantially as shown.
